Patented July 6, 1920.

UNITED STATES PATENT OFFICE.

CLARENCE W. HOBBS, OF WORCESTER, MASSACHUSETTS; CLARENCE W. HOBBS, JR., AND SAMUEL T. HOBBS ADMINISTRATORS OF SAID CLARENCE W. HOBBS, DECEASED.

SAFETY DEVICE.

1,345,442.

Specification of Letters Patent. Patented July 6, 1920.

Application filed October 2, 1916, Serial No. 123,229. Renewed March 4, 1920. Serial No. 363,287.

To all whom it may concern:

Be it known that I, CLARENCE W. HOBBS, a citizen of the United States, residing at Worcester, in the county of Worcester and 5 Commonwealth of Massachusetts, have invented a new and useful Improvement in Safety Devices, of which the following is a specification, accompanied by drawings forming a part of the same.

10 My present invention relates to a safety device adapted to be applied to that type of machines which embody stationary and reciprocating work engaging elements, such for example as punching machines, die 15 presses, and staying machines for applying a stay or reinforcing strip to the corners of pasteboard boxes.

15 The object of my invention is to provide means for automatically rendering the work 20 engaging elements inoperative whenever an obstruction is placed between them. The useful purpose of my present invention is to prevent injury to the hand of an operator in case it is placed between the work engaging 25 elements.

20 In the accompanying drawings I have shown my invention as applied to a machine for applying corner stays to pasteboard boxes, and I have shown only so much of 30 the corner staying machine as is necessary to illustrate the character of my invention.

25 In the accompanying drawings, Figure 1 denotes a side elevation of so much of a corner staying machine as is necessary to illustrate my present invention, a portion of said 35 figure being shown in sectional view. Fig. 2 is a front elevation of the same, similar parts being indicated by similar reference characters in the different figures.

40 Referring to the accompanying drawing, 1 denotes a base or stand upon which the machine is mounted. 2 is a framework supporting the operative mechanism. In the framework 2 is journaled a shaft 3 carrying 45 upon one end a belt pulley 4 by which power is applied to the machine, and upon the opposite end is a disk provided with a crank pin 5. The crank pin 5 is connected by a link 6 with a stud or wrist pin 7, projecting 50 from a slide 8, whereby a vertically reciprocating movement is given to the slide in ways supported by the framework of the machine. Carried by the slide 8 is an angular die 9 having the usual yieldable connection

with the slide. The angular die 9 constitutes the reciprocating work engaging member and it coöperates with an angular anvil 10 for the purpose of pressing an adhesive stay strip upon the corner of a pasteboard box, when the latter is supported by its corner upon the anvil.

55 Means for feeding the stay strip between the die 9 and anvil 10, and for applying adhesive material to the under side of the stay strip usually form component parts of the 60 staying machine, but these mechanisms are omitted in the present drawings as they are not concerned in the embodiment of my present invention. The anvil 10 is mounted upon one end of a bar 11 which is pivoted at its 65 opposite end upon a spindle 12 carried in a sleeve 13 capable of sliding in ways 14 mounted upon the framework of the machine. Attached to the under side of the sleeve 13 is a rack 15 which is engaged by a 70 pinion 16 carried upon the end of a spindle 17 projecting from the side of the framework in convenient position to receive a wrench by which the spindle and pinion may be rotated in order to move the sleeve 13 75 back and forth in ways 14, to provide for different lengths of stay strips. The sleeve 13 is cut away beneath the bar 11, as shown at 18, Fig. 1, in order to allow the free end of the bar 11, and the anvil carried thereby 80 to fall by gravity into a position to bring the anvil 10 below the path of the vertically reciprocating die 9.

85 The bar 11 carrying the anvil 10 is provided upon its under side with a block 19, 90 the inner end of which rests upon a spindle 20 which is forced upwardly by a small spiral spring 21 in order to normally hold the anvil 10 in its raised position. In case an obstruction is placed between the die 9 95 and the anvil 10, such for example as the finger of an operator, the spring 21 will yield without inflicting injury. In order to enable the requisite pressure to be applied to the stay strip a sliding block or gag 22 is 100 provided, resting upon the framework of the machine and of sufficient thickness to fill the space between the frame supporting the gag and the block 19. The gag 22 is carried upon one end of a rod 23 pivotally connected 105 at its outer end with a lever 24 extending downwardly from a hub 25 which is pivoted upon a stud 26 projecting from the

framework of the machine. The hub 25 is provided with an arm 27 carrying at its free end a cam roll 28. The roll 28 is held against the periphery of a cam 29 by means of a torsional spring 30 wound upon the hub 25. The cam 29 is attached to the shaft 3 and is provided with a shoulder 31. The cam 29 is so timed with relation to the downward movement of the die 9 that when the latter 10 approaches so near the anvil that the finger of the operator can not be inserted between the die and the anvil the cam roll will reach the shoulder 31, allowing the lever 24 to be quickly swung by the action of the spring 15 30 to slide the gag beneath the block 19 and thereby render the anvil rigid.

As the die rises, the cam 29 will gradually draw the gag back from beneath the block 19 until it reaches the position shown 20 at 22, Fig. 2.

The anvil is therefore capable of being depressed during the downward movement of the die 9 by any object interposed between the die and anvil. However, when the die 25 reaches the anvil sufficiently near to prevent the introduction of the finger of the operator, then the gag will be inserted beneath the block 19 by the action of the spring 30 as controlled by the cam 29.

30 I claim:

1. In a machine of the class described, a yieldable stationary work engaging member, a reciprocating work engaging member coöperating with said yieldable member, 35 means for actuating said reciprocating member, and means operable by said actuating means for rendering said yieldable member rigid at a predetermined point in the movement of said reciprocating member.

40 2. In a machine of the class described, a yieldable stationary work engaging member, a reciprocating work engaging member coöperating with said yieldable member, means for actuating said reciprocating member, 45 and automatic means for rendering said yieldable member rigid at a predetermined point during the approach of said reciprocating member toward said yieldable member.

50 3. In a machine of the class described, a reciprocating member for applying pressure to the work, a normally yieldable stationary member for receiving pressure applied to the work, a spring for supporting said stationary member in its normal position, and 55 means for locking said yieldable member

in its normal position as the reciprocating member approaches said yieldable member within a predetermined distance.

4. In a machine of the class described, a reciprocating work engaging member, a bar pivoted at one end and extending across the line of travel of said reciprocating member and at right angles thereto, a work engaging member carried by the free end of said bar, a spring yieldably supporting said bar, a gag for locking said bar against movement, and means for actuating said gag to lock said bar in timed relation to the movement of said reciprocating member. 70

5. In a machine of the class described, a reciprocating work engaging member, a yieldable stationary work engaging member coöperating with said reciprocating member, means for yieldably supporting said stationary member in its normal position relatively to said reciprocating member, and means for moving said yieldable stationary member in a line at right angles to the line of movement of said reciprocating member. 75

6. In a machine of the class described, a reciprocating work engaging member, a yieldable stationary work engaging member coöperating with said reciprocating member, a rotatable member for actuating said reciprocating member, a movable gag for locking said yieldable stationary member in its normal position, and means carried by said rotatable member for controlling the movement of said gag. 80

7. In a machine of the class described, a reciprocating work engaging member, a rotatable member for actuating the same, a yieldable stationary work engaging member coöperating with said reciprocating member, 95 a movable gag for locking said yieldable stationary member in its normal position, a spring for moving the gag into its locking position, and a cam carried by said rotatable member for withdrawing said gag from its locking position. 100

8. In a machine of the class described, a pair of coöperating pressing members, one of said members being yieldably supported, and means responsive to the movement of the other member for procuring the unyielding support of said first member. 105

CLARENCE W. HOBBS.
